United States Patent

Des. 241,645

Patented Sept. 28, 1976

241,645

GAS LIGHTER

Ralph Lanzi, 108 St. Stephens Place,
Staten Island, N.Y. 10306

Filed Nov. 6, 1975, Ser. No. 629,651

Term of patent 14 years

Int. Cl. D23—03

U.S. Cl. D23—90.1

FIG. 1 is a front elevational view of a gas lighter showing my new design;

FIG. 2 is a rear elevational view;

FIG. 3 is a plan view;

FIG. 4 is a bottom plan view with the ring folded against the base portion of the gas lighter;

FIG. 5 is an elevational view, with a lower part thereof in section as seen from the plane 5—5 in FIG. 1; and

FIG. 6 is a bottom plan view of the cover member seen in section in FIG. 5.

I claim:

The ornamental design for a gas lighter, substantially as shown.
